UNITED STATES PATENT OFFICE

139,569

DESIGN FOR A CLEANING BUCKET

Elizabeth O'Brien, Davenport, Iowa

Application May 29, 1944, Serial No. 113,798

Term of patent 14 years

(CL. D58—17)

To all whom it may concern:

Be it known that I, Elizabeth O'Brien, a citizen of the United States, residing at Davenport, in the county of Scott and State of Iowa, have invented a new, original, and ornamental Design for a Cleaning Bucket, of which the following is a specification, reference being made to the accompanying drawing, forming a part thereof.

In the drawing,

Fig. 1 is a perspective view of a cleaning bucket embodying my new design; and

Fig. 2 is a plan view thereof.

I claim:

The ornamental design for a cleaning bucket, substantially as shown.

ELIZABETH O'BRIEN.
